(57) **CLAIM**

The ornamental design for an electric truck, as shown and described.

DESCRIPTION

FIG. 1 is a top-front perspective view of an electric truck. FIG. 2 is a bottom-rear perspective view of the electric truck shown in FIG. 1.

FIG. 3 is a right-side elevation view of the electric truck shown in FIG. 1.

FIG. 4 is a front elevation view of the electric truck shown in FIG. 1.

FIG. 5 is a left-side elevation view of the electric truck shown in FIG. 1.

FIG. 6 is a rear elevation view of the electric truck shown in FIG. 1.

FIG. 7 is a top plan view of the electric truck shown in FIG. 1; and,

FIG. 8 is a bottom plan view of the electric truck shown in FIG. 1.

The broken lines represent portions of the electric truck that form no part of the claimed design.

1 Claim, 8 Drawing Sheets
